CLAIM

We claim the ornamental design for a battery pack adapter, as shown and described.

DESCRIPTION

FIG. 1 is a top perspective view of a battery pack adapter. FIG. 2 is another top perspective view of the battery pack adapter.

FIG. 3 is a bottom perspective view of the battery pack adapter.

FIG. 4 is a top view of the battery pack adapter.

FIG. 5 is a bottom view of the battery pack adapter.

FIG. 6 is a first side view of the battery pack adapter.

FIG. 7 is a second side view of the battery pack adapter.

FIG. 8 is a first end view of the battery pack adapter; and,

FIG. 9 is a second end view of the battery pack adapter.

Portions of the battery pack adapter shown in broken lines form no part of the claimed design.
